UNITED STATES PATENT OFFICE.

RUDOLPH MAGOSY, OF BROOKLYN, NEW YORK.

MUTE FOR MUSICAL INSTRUMENTS.

Application filed February 4, 1927. Serial No. 165,773.

The subject of this invention is an improved mount for mutes.

As is well known, when say a wind instrument, of the horn type, as a cornet, is to be played with reduced sound volume, as indoors, such volume may be thus reduced or muted by temporarily inserting and securing in the bell-end of the horn a suitably shaped mute, generally conical over say a 10 part of its length. Such body is commonly mounted in the horn to provide a tone column length in the horn of annular cross-section, or of interrupted annular cross-section at the location of the mounting means for securely but impermanently holding the mute 15 in place in the horn. Such mounting means has commonly involved a plurality of protuberances spaced around the mute, and these protuberances have commonly been frictional 20 pads of a suitable material. Cork has been the material largely adopted. Heretofore, such protuberances have been merely adhesively or otherwise insecurely carried by the mute, so that often on taking the mute 25 from its case to mount the same in the horn, these protuberances have been found to be detached from the mute or not at all securely mounted thereon, or in inserting the mute, to wedge the same in place by slightly compressive action on the protuberances, or in pulling the mute free of its frictional or wedge engagement in the horn, to remove the mute, the protuberances have been displaced or 30 wrenched loose from the mute.

The particular object of the present invention is to provide a novel and improved mounting means for such protuberances, whatever their material, whether cork or otherwise.

The invention will be fully understood, and 40 other objects and advantages thereof become apparent, from the following description, when taken in connection with the accompanying drawing illustrating a preferred form of the invention, and also certain variations of such form. It is to be understood, of course, that said form is merely one of the many possible embodiments of the invention, and consequently, the illustrated variations are merely variations of the one form selected 45 for illustration in the drawing; the scope of protection contemplated, of course, being indicated solely by the appending claims.

In the drawing:

Fig. 1 shows said form in side elevation,

in full lines, a horn element being indicated 55 in dot and dash lines;

Fig. 2 is a transverse section, taken on line 2—2 of Fig. 1;

Fig. 3 is an enlarged fragmentary transverse section, taken say on a line corresponding to the line 2—2 of Fig. 1, showing one possible variation;

Fig. 4 is a view similar to Fig. 3, showing another possible variation;

Fig. 5 shows a part of the mute in side 65 elevation, and one of the aforesaid protuberances, hereinafter called the pads, being inserted in the type of mount illustrated generally in all the views; and

Fig. 6 is a fragmentary view, partially in 70 section and partially in perspective, showing still another variation.

Similar reference characters refer to similar parts throughout the several views of the drawing.

A conventional mute is indicated at 7, in Fig. 1, as impermanently but securely wedged in place in a horn indicated at 8. The positioning and wedging instrumentalities are a plurality of pads 9, which may 80 well be of cork. As is well known, cork is a material having good frictional qualities, and is also rather readily compressible, and, further, is elastically compressible, and at the same time rather easily deformable.

Three of such pads 9 may conveniently be employed, as illustrated in Figs. 1 and 2. As is common practice, the mute here shown is a hollow body having comparatively thin walls of a suitably stiff material, say thin 90 metal. At the intended location of each pad 9, this wall material of the mute, is partially cut away and struck up to form a plurality of tongues or equivalents, between each which set of tongues each pad 9 is adapted to be positioned and crimped or wedged in place, or otherwise more securely held than by the familiar adhesive application, on the mute.

In the form of the invention shown in Figs. 1 and 2, and in the mute structure 100 shown in Fig. 5, five of these tongues are provided at each pad location. What may be termed the forward side pair of tongues are indicated at 10, and what may be termed the rear side pair of tongues are indicated at 11, 105 while an end tongue is indicated at 12; in Figs. 1 and 2. In the cases of the variations of Figs. 3, 4 and 6, similar pairs of side tongues

may be provided, although only one of such pairs is shown in each of these views; while also, an end tongue, like that shown at 12, may be provided, at the inner or outer end, or 5 at both ends of the pad.

In the case of Figs. 1 and 2, and in the case of Fig. 4, the side tongues, in the last-mentioned view marked 11^a, are slightly inwardly bent; while in Figs. 3 and 5, they are substantially parallel. In Fig. 5 the side tongues are 10 marked 11'; the end tongue shown being marked 12'. In these variations, as well also as in the variation of Fig. 6, wherein the side tongues, which are here marked 11^b, the pads 15 9 may be so laterally dimensioned, as to have a squeeze-fit between the appointed side-tongues, or/and may have side grooves cut therein where the side-tongues are inwardly bent, as indicated most clearly at 9^a in Fig. 6.

20 A pad 9 may be very conveniently squeezed into place between its mounting means where such means are any of those shown in the drawing, as indicated by the arrow shown in Fig. 5.

25 Figs. 3, 4 and 6 illustrate further variations. Here there is provided, so as to be finally interposed between the base of a pad, and the underlying mute-wall portion, a fairly rigid strip, of suitable material, say thin 30 hard rubber, metal, or the like, as indicated at 14. Such strip may be disconnected from pad as well as mute, or suitably secured to either. When carried by the pad, the strip 14, particularly when the side tongues are 35 inwardly bent, aids in the security of the attachment of the pad to the mute, by holding the base-portion of the pad relatively unyielding to lateral deformation, as compared to the upper portions of the pad.

40 By using a single end tongue, a pad may be 45 slidingly forced into place as shown in Fig. 5; and by positioning such end tongue at that end of a pad location nearer the larger end of the mute, as at 12 or 12', no slippage tendency can ever be set up as between pad and side 50 tongues 11 or equivalents, on wedge-mounting the mute in a horn. These wedge-mounting operations have heretofore been the principal causes of pad loosening and displacement; as

there is no wedging action, but on the contrary a wedge relieving action, in removing the mute from a horn.

Inasmuch as many changes could be made in the above constructions, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language contained in the following claims is intended to cover all the generic and specific features of the invention herein described and all 65 statements of the scope of the invention which, as a matter of language, might be said to fall therebetween.

I claim:

1. In a mute for wind musical instruments, 70 the combination with a pad, of means for wedge-mounting the pad impermanently in place, on the mute, said wedging means including a plurality of tongues struck up from a wall element of the mute.

2. In a mute for wind musical instruments, in combination, a plurality of pads, and means for mounting the pads on the mute including exterior projections mounted directly on the wall of the mute, such projections 80 forming pockets at each desired pad location.

3. In a mute for wind musical instruments, in combination, a plurality of pads, and means for mounting the pads on the mute including exterior projections mounted directly on the wall of the mute, such projections 85 forming pockets at each desired pad location, said pads being of a material which is elastically deformable, whereby a pad may be 90 wedgingly mounted in a pocket.

4. In a mute for wind musical instruments the combination with a plurality of pads, of means for wedge-mounting the pad impermanently in place on the mute, said wedging means including a plurality of tongues struck 95 up from a wall portion of the mute.

In testimony whereof I affix my signature.
RUDOLPH MAGOSY.
